GRAIN SCOURING MACHINE

John A. McBrady, Valley City, N. Dak.

Application January 13, 1936, Serial No. 58,805

7 Claims. (Cl. 83—32)

My invention relates to grain scouring machines and to machines for removing from the grain the particles of beard, tips, etc., separated from the grain in the scouring thereof, and has 5 for an object to provide a machine of such character which will be highly efficient in operation.

Another object of the invention resides in providing a grain scouring machine which will be highly practical and simple in construction.

10 A still further object of the invention resides in providing a grain scouring machine in which the grain is projected against a corrugated surface.

Another object of the invention resides in providing a grain scouring machine in which the grain is deposited upon a reticulate member and thrown by centrifugal force from said member and against a corrugated surface and in which the screenings through said reticulate member 20 are removed from the machine separately from the scoured grain.

An object of the invention resides in providing a grain scouring machine having a vertically extending shaft provided with a number of spaced 25 discs thereon and a case encircling said shaft together with means operated by the shaft for throwing the grain deposited upon the discs outwardly therefrom by centrifugal force and against the inner walls of the case.

30 A feature of the invention resides in providing hoppers for collecting the grain discharged from certain of said discs and depositing it upon other of said discs.

Another object of the invention resides in constructing the walls of the case with the corrugations against which the grain is thrown.

A still further object of the invention resides in constructing the case rectangular in cross section.

An object of the invention resides in constructing 40 the discs reticulate and in forming the shaft hollow and with openings communicating with the space within the case immediately below the discs.

A feature of the invention resides in providing 45 funnels encircling the shaft connected to the reticulate discs and to the shaft below the openings therein for directing the screenings through the discs into the shaft.

An object of the invention resides in providing 50 suction means for removing the screenings through the reticulate discs.

Another object of the invention resides in connecting the suction means to said hollow shaft.

Other objects of the invention reside in the 55 novel combination and arrangement of parts

and in the details of construction hereinafter illustrated and/or described.

In the drawing:

Fig. 1 is a longitudinal sectional view of a grain scouring machine illustrating an embodiment of 5 my invention.

Fig. 2 is a plan sectional view taken on line 2—2 of Fig. 1 and drawn to a larger scale.

Fig. 3 is a plan sectional view similar to Fig. 2 and taken on line 3—3 of Fig. 1. 10

In the scouring of grain by the ordinary methods it has been customary to remove the beards, ends, etc. by throwing the grain by centrifugal force against a fixed surface. Such methods are highly inefficient in that the grain only strikes 15 the surface but a single time during each operation. This makes the method slow. With such machines the separation of the loosened matter from the clean grain has been accomplished by independent separating devices. The present 20 invention overcomes these objections by providing a machine in which the grain strikes the surface against which it is thrown a number of times during each operation so that less operations are necessary than would otherwise be required. At the same time the matter removed 25 from the grain is automatically separated therefrom and discharged from the machine, thereby eliminating subsequent separation.

My invention comprises a framework indicated 30 in its entirety by the reference character A, which rotatably supports a rotor B. Framework A also carries a case C which surrounds the rotor B and functions in a manner to assist in the scouring of the grain as will be presently more 35 fully described. These various parts will now be described in detail.

The framework A comprises a base 10 which is provided with two skids 11 and 12 connected together by means of two cross frame members 13 40 and 14, welded thereto. Attached to the skids 11 and 12 and to the cross members 13 and 14 are four uprights 15, 16, 17 and 18 which are secured together at their upper ends through cross frame members 19. The skids and the various frame 45 members may, if desired, be constructed of angle iron or some other similar material and are riveted, bolted or welded together.

The case C comprises four walls 21, 22, 23 and 24 and the three walls 22, 23 and 24 are riveted 50 or bolted to the flanges of the angle uprights 15, 16, 17 and 18. The other wall 21 serves as a door and closes a doorway 25 formed in a door frame 26. This door frame is attached to the uprights 15 and 18. The door 21 is hingedly connected to 55

the frame 26 by means of hinges 20 and is provided with one or more bolts 27 or other fastening members along its other edge by means of which said door may be held in position. The 5 case C reaches to the floor or other surface on which it rests, being thus closed at its lower end. The walls 21, 22, 23 and 24 of case C are provided with vertically extending corrugations 28 which provide corrugated surfaces 29 upon the interior 10 of the case extending throughout the height thereof. These corrugations function in a manner to be presently more fully described.

The rotor B includes a hollow or tubular shaft 31 which is formed with a bore 32 extending 15 throughout the length of the same. Bore 32 is closed at the upper end by means of an end wall 33 welded to shaft 31. The shaft 31 is journaled in two bearings 34 and 35. These bearings are 20 identical in construction and are supported by the framework A in the same manner. For this reason only bearing 34 and its support will be described in detail. The bearing 34 may be of any suitable type and for the purpose of illustration a plain bearing has been shown. This bearing 25 comprises a body 36 and a cap 37 therefor which is removably attached to said body by means of bolts 38. Bearing 34 is supported by means of two brackets 41 and 42 which may be constructed of strap iron bent in the form shown 30 in Fig. 2 and which are attached to the flanges of the frame member uprights 15, 16, 17 and 18. The shaft 31 may be inserted into the case through the doorway 26 and when properly positioned, the caps 37 of the bearings which face said doorway 35 may be applied to the bearings to rotatably support the shaft within its bearings.

Shaft 31 is driven by means of a bevel gear 43 which is secured to said shaft and which is constructed with a hub 44 resting upon the bearing 40 35. This hub holds the shaft 31 from downward longitudinal movement in its bearings. To prevent upward longitudinal movement of the shaft 31, a collar 45 is provided which is secured to the shaft and engages the bearing 35 upon the under surface thereof. Bevel gear 43 meshes 45 with another bevel gear 46 which is attached to a countershaft 47. This countershaft is journaled in bearings 48 which are carried by cross frame members 49 secured to the uprights 15 and 50 16. The countershaft 47 has attached to it upon the exterior of the case a sprocket wheel 51. A chain 52 passes over this sprocket wheel and another sprocket wheel 53 rotatably mounted on a stub shaft 54 secured to a bracket 55 which is 55 attached to the upright 15 by means of bolts 56. A pulley 57 is connected to the sprocket wheel 53 and serves to drive the counter-shaft 47. The device may be operated by the said pulley or in place thereof a crank may be used whereby the 60 device may be manually operated.

Shaft 31 has attached to it a number of spaced discs 58 which are of a diameter somewhat less than the inner transverse dimensions of the case. These discs may be brazed, welded or otherwise 65 secured to the shaft. The discs 58 are reticulate, being constructed with perforations 59 of such dimensions that the dust, whiskers, tips, chaff and other matter removed from the grain may pass through the perforations and yet prevent 70 the passage of grain through the same. Superimposing the discs 58 are blades 61 which are secured to said discs and to the shaft by brazing, welding, or otherwise, and which serve to throw the grain deposited upon the discs outwardly by 75 centrifugal force. Immediately below the discs

58 are provided funnels 62 which engage the under surface of the said discs at localities outwardly from the perforations 59. These funnels are also attached to the shaft 31 in the same manner as the discs 58 and blades 61. The shaft 31 is provided with openings 63 extending therethrough which are situated between the lowermost portions of the funnels 62 and the discs 58. Any dust or foreign material which passes through the perforations 59 is guided by these 10 funnels into the bore 32 of the shaft 31 through the openings 63.

In the operation of the machine, the grain deposited upon the discs 58 is thrown outwardly by centrifugal force by means of the blades 61 15 whereby it strikes the corrugated surfaces 29 of the case C. The impact of the grain against these surfaces breaks off the whiskers, ends and other parts of the grain desired to be removed therefrom through the scouring action afforded. Due 20 to the use of the corrugated surfaces the grain bounces from one corrugation to the other, thereby striking the surface several times during each operation. For the purpose of directing the grain striking the surfaces 29 of the case C 25 back to the discs 58 a number of hoppers 64 are employed. These hoppers have three converging walls 65, 66 and 67 and are open at the front of the case. At the edges 68 of hoppers are provided 30 grooves, not shown, which receive the fourth wall 69 of the hoppers. The walls 65, 66, 67 and 69 are constructed with flanges 71 which fit against the inner walls of the case and by means of which the hoppers are attached to the case. At the center of each hopper is provided 35 an opening 72 preferably circular, which is concentric with the shaft 31 and which directs the grain deposited upon the hopper to the center of the disc below it. By means of the hoppers and the structure carried by the shaft 31, the grain is successively thrown by the discs outwardly against the walls of the case and thereafter grain deposited upon the discs so that the grain finally travels downwardly throughout the 40 height of the machine.

In order to direct the grain into the machine a hopper 73 is employed which is situated at the top of the machine and which is attached to the cross frame members 19. This hopper has an outlet 74 disposed to one side of the shaft 31 45 50 which discharges upon the uppermost of the discs 58. A slide 75 is guided for transverse movement by means of a guide 76 to open and close the outlet 74 so that the amount of grain fed to the machine can be controlled at will.

For the purpose of removing the scoured grain from the machine a hopper 77 similar to the hoppers 64 is employed which is disposed immediately below the lowermost disc 58. The hopper 77 is attached to the case C in the same manner 60 as the hoppers 64. This hopper is constructed with an inclined bottom 78 which terminates in a spout 79 extending through the wall 23 of the case. A sleeve 81 attached to the wall 78 of hopper 77 is surrounded by another sleeve 82 attached to shaft 31 and rotatable with said shaft. By means of this construction, dust is prevented 65 from passing through the joint between the shaft 31 and the hopper 78.

Removal of the dust and other foreign matter 70 separated from the grain through the reticulate discs is accomplished by means of a suction fan indicated in its entirety by the reference numeral 83. This suction fan may be constructed in accordance with the usual practice and comprises a 75

case 84 in which is rotatably mounted a rotor 85. A bearing 86 is attached to the case 84 and journals a shaft 87 to which the rotor 85 is rigidly secured. The shaft 87 extends through the wall 5 22 of case C and has attached to it at the protruding end thereof a sprocket wheel 88. A chain 89 passes over the sprocket wheel 88 and another sprocket wheel 91 secured to countershaft 47. By means of this construction the suction fan 10 is operated in the usual manner. The case 84 is supported by means of two brackets 92 which are attached to the same and to the uprights 15 and 16 of the framework of the machine.

For the purpose of bringing the shaft 31 into communication with the suction fan 83 an elbow 93 is provided which is constructed at one end with a bore 94 into which the lower end 95 of shaft 31 extends. Shaft 31 is rotatably mounted in said bore and forms a fairly snug fit with the 20 elbow so that leakage of air past the same is prevented. Elbow 93 is also constructed with a flange 96 which is bolted to the case 84 opposite the center of the rotor 85 by means of bolts 97. Case 84 is also constructed with an outlet 98 25 which has attached to it a spout 99 arranged in inclined relation with respect to said suction fan so that matter collected thereby may flow by gravity out of the machine. To permit of the entry of air into the machine, the walls 21, 22, 23 30 and 24 of case C are constructed with openings 101 which are situated immediately below the hoppers.

The method of assembling the invention is as follows: The shaft 31 is constructed with the discs and funnels and sleeve attached to the same. Sleeve 81 is next threaded upon the end 95 of said shaft and gear 43 and collar 45 next applied thereto. The caps 37 of the bearings 34 and 35 are next removed and likewise all of the sliding 40 walls 69 of the hoppers 64. The shaft 31 with attached parts is next inserted into the case through the doorway 25 and the shaft placed within the bearings 34 and 35. After the shaft is applied the sleeve 81 is adjusted so that the 45 same rests upon the wall 78 of hopper 71. Caps 37 are next bolted to the bearings and the gear 43 raised or lowered until the discs have the proper relation with respect to the hoppers. The collar 45 is next fixed in the proper position and 50 the various walls 69 of the hoppers replaced. Suction fan 83 is next inserted into the case C in such a manner that the shaft 31 extends into the elbow 93. Brackets 92 supporting said suction fan are then attached to the uprights 15 and 55 16. The two chains 52 and 89 are next applied to the sprockets and the device is ready for operation.

The operation of the invention is as follows: The grain, upon being deposited in the hopper, is 60 fed through the outlet of said hopper, onto the uppermost of the discs 58. The flow of grain is controlled by the slide 75 so that the desired amount of grain may pass through the machine. The grain upon striking the first disc 58 is thrown 65 outwardly through centrifugal force by means of the blades 61 associated therewith and strikes the corrugated surface 29 of the case C. During such action the grain is being scoured and when the grain has lost its impetus, drops upon the 70 uppermost of the hoppers 64. This hopper directs the grain upon the disc 58 next to the uppermost disc, where the same action is repeated. The grain thus travels alternately from disc to hopper until it is finally deposited on the 75 hopper 71 and discharged from the machine.

through spout 79. While the scouring action is taking place the dust, whiskers, ends and other matter on the grain which it is desired to remove by the scouring process, is screened through the perforations 59 of the reticulate discs 58 and 5 passes into the various funnels 62 attached to shaft 31. This action is aided by the suction fan 83 which causes the flow of air through the reticulate discs and into said shaft. By arranging the openings 101 at the localities specified 10 escape of dust from the machine is prevented and the air is led through the machine in an extremely practicable and efficient manner. The suction fan 83 discharges the air, dust and other matter separated from the grain through the spout 79 15 which may be connected to a suitable dust collector in which the air and dust are separated or said spout may be led directly to the exterior as desired.

My invention is extremely simple and practical 20 in operation and functions in a highly efficient manner. In addition to scouring the grain the removed matter is simultaneously separated from the grain so that the grain leaves the machine in a clean condition. By the use of the corrugated 25 surfaces upon the interior of the case, greater scouring action is procured and less power is required in the scouring of the grain. My machine may be operated either manually or by power 30 and may be used for either test purposes or for the purpose of scouring grain preparatory to grinding into flour. My invention is exceedingly compact and occupies a minimum amount of floor space. The various parts of the invention may 35 be easily assembled and taken apart for the purpose of cleaning and repair whenever necessary.

Changes in the specific form of my invention, as herein disclosed, may be made within the scope of what is claimed without departing from the 40 spirit of my invention.

Having described my invention, what I claim as new and desire to protect by Letters Patent is:

1. A grain scouring machine including a vertically extending hollow shaft, a plurality of spaced discs attached to said shaft, means operated by the shaft for throwing grain deposited upon the discs outwardly therefrom by centrifugal force, enclosing means extending about 45 said discs and against which the grain discharged from the discs is projected, hoppers for collecting the grain discharged from certain of said discs and depositing it upon other of said discs, said discs being provided with perforations and said shaft having openings therein situated immediately below said discs, and means connected 50 with said hollow shaft for drawing screenings removed by the perforations in the discs through said openings and shaft and discharging the same exteriorly of the case.

2. A grain scouring machine including a vertically extending hollow shaft, a plurality of spaced discs attached to said shaft, means operated by the shaft for throwing grain deposited upon the discs outwardly therefrom by centrifugal force, enclosing means extending about 65 said discs and against which the grain discharged from the discs is projected, hoppers for collecting the grain discharged from certain of the discs and depositing it upon other of the discs, said discs being provided with perforations and 70 said shaft having openings therein situated immediately below said discs, funnels encircling said shaft and disposed below said discs, said funnels being connected to the discs outwardly of the perforations therein and to the shaft below the 75

openings therein and guiding the screenings from the perforations of the disc into said shaft.

3. A grain scouring machine including a vertically extending hollow shaft, a plurality of spaced discs attached to said shaft, means operated by the shaft for throwing grain deposited upon the discs outwardly therefrom by centrifugal force, enclosing means extending about said discs and against which the grain discharged from the discs is projected, hoppers for collecting the grain discharged from certain of the discs and depositing it upon other of said discs, said discs being provided with perforations and said shaft having openings therein situated immediately below said discs, funnels encircling said shaft and disposed below said discs, said funnels being connected to the discs outwardly of the perforations therein and to the shaft below the openings therein and guiding the screenings from the perforations of the disc into said shaft, and suction means connected with said shaft.

4. A grain scouring machine including a vertically extending hollow shaft, a plurality of spaced reticulate discs attached to said shaft, means operated by the shaft for throwing the grain deposited upon the discs outwardly therefrom by centrifugal force, enclosing means extending about said discs and having a corrugated surface against which the grain discharged from the discs is projected, hoppers for collecting the grain discharged from certain of said discs and depositing it upon other of said discs, said shaft having openings therein disposed immediately below said discs, funnels encircling said shaft and connected to said discs near the peripheries thereof and to said shaft below said openings, and suction means connected to said shaft.

5. A grain scouring machine including a vertically extending shaft, a plurality of spaced reticulate discs attached to said shaft, one above the other, means operated by the shaft for throw-

ing the grain deposited upon the discs outwardly therefrom by centrifugal force, enclosing means extending about said discs and against which the grain is projected, hoppers for collecting the grain discharged by centrifugal force from each disc and depositing it upon the disc immediately below the same and a plurality of collecting devices, one for each disk for receiving the screenings passing through said disks and means for removing the screenings collected by collecting devices.

6. A grain scouring machine including a vertically extending shaft, a plurality of spaced reticulate discs attached to said shaft, one above the other, means operated by the shaft for throwing the grain deposited upon the discs outwardly therefrom by centrifugal force, enclosing means extending about said discs and against which the grain is projected, hoppers for collecting the grain discharged from each of said discs and depositing it upon the discs immediately below the same, funnels disposed below said reticulate discs for collecting the screenings passing through said discs, and means for collecting the screenings from all of said funnels.

7. A grain scouring machine including a vertically extending shaft, a plurality of spaced reticulate discs attached to said shaft, means operated by the shaft for throwing the grain deposited upon the discs outwardly therefrom by centrifugal force, enclosing means extending about said discs and against which the grain is projected, hoppers for collecting the grain discharged from certain of said discs and depositing it upon other of said discs, funnels disposed below said reticulate discs for collecting the screenings passing through said discs, and suction means for collecting the screenings from all of said funnels.

JOHN A. McBRADY. 40
